ATTY'S.

UNITED STATES PATENT OFFICE.

FRANK CARSON FANE, OF ELMFSORD, NEW YORK.

COMBINATION BELT AND SUSPENDERS.

1,271,554.

Specification of Letters Patent. Patented July 9, 1918.

Application filed April 8, 1918. Serial No. 227,320.

To all whom it may concern:

Be it known that I, FRANK CARSON FANE, a citizen of the United States, and resident of the town of Elmsford, in the State of 5 New York, United States of America, have invented certain new and useful Improvements in Combination Belts and Suspenders, of which the following is a specification.

This invention relates to improvements in 10 combination belts and suspenders, and the objects of the invention are to provide a simple and effective belt which may be readily attached to the trousers and which will also form an attaching means for suspenders.

15 Further objects are to effectively support the trousers by such a device and hold the waist band neatly and firmly in position, and it consists essentially of the improved construction hereinafter described in detail in 20 the accompanying specification and drawings forming part of the same.

In the drawings;

Figure 1 is a perspective view of the invention showing the same on the top of a 25 pair of trousers.

Fig. 2 is a perspective view of the belt shown separately.

Fig. 3 is a perspective view of a portion of the belt open.

30 Fig. 4 is a perspective view showing additional clamping means which may be employed if desired.

Fig. 5 is a perspective view showing a 35 suitable clasp for the ends of these suspenders.

In the drawings like characters of reference indicate corresponding parts in all the drawings.

Referring to the drawings, A represents 40 the belt formed of an outer section 10 and an inner section 11 adapted between them to embrace the waist band of the trousers being held against this waist band by suitable clamping means.

45 In Fig. 3, I have shown a spring hinge device 12 connecting the sections 10 and 11 and having a spring hinge 13 by which the plates 14 and 15 are clamped together, which said plates may have engaging projections 50 16 therein to enable them to better grip the waist band of the trousers.

Additional clamping means may, if desired be provided on the outside in the form

of clamping plates 18 and 19 connected by a spring hinge 20.

A suitable buckle 17 may be provided on the end of the outer section 10.

To enable the suspenders to be connected to the trousers through the belt, the belt is provided at intervals with engaging eyes or loops 21 conveniently formed of metal and secured to the belt. These eyes are adapted to receive suitable engaging hooks 22 on the suspenders B, the latter being of any suitable design.

A safety pocket 23 may if desired be suspended from the inner section 11 of the belt.

It will be seen that the present invention provides a simple and convenient device by which the trousers or pantaloons may be supported without buttons or other fastening means on the trousers.

A device of this kind is of special use on active military service, where suspenders or buttons are not easily replaced.

As many changes could be made in the above construction and many apparently widely different embodiments of my invention within the scope of the claims may be constructed without departing from the spirit or scope thereof, it is intended that all matter contained in the accompanying specification and drawings shall be interpreted as illustrative and not in a limiting sense.

What I claim as my invention is:

1. A belt of the character described comprising an inner and outer section folded one upon the other, means for clamping the sections together, upon the edge of the article to be supported.

2. A belt comprising an inner and outer section, a pocket on the outer section, clamping means between the two sections comprising plates, and a spring hinge connecting the plates, a plurality of lugs extending at intervals on the upper edge of the belt.

3. A belt comprising an inner and outer section, a pocket on the outer section, clamping means between the two sections comprising plates, and a spring hinge connecting the plates, a plurality of lugs extending at intervals on the upper edge of the belt, and suspenders having hooks to engage the eyes.

In witness whereof I have hereunto set my hand.

FRANK CARSON FANE.
